[57] CLAIM

The ornamental design for an element of a cartridge for an electrophotographic printer, as shown.

DESCRIPTION

FIG. 1 is a rear elevational view of an element of a cartridge for an electrophotographic printer showing our new design, the front elevation view of the element being a mirror image thereof;

FIG. 2 is a rear elevational view of an element of a cartridge for an electrophotographic printer showing an additional embodiment of our new design, the front elevation view of the element being a mirror image thereof;

FIG. 3 is a rear elevational view of an element of a cartridge for an electrophotographic printer showing our new design, the front elevation view of the element being a mirror image thereof;

FIG. 4 is a top rear perspective view;

FIG. 5 is a bottom rear perspective view;

FIG. 6 is a right side elevational view thereof; and,

FIG. 7 is a left side elevational view thereof.

The broken line showing of a cartridge in FIGS. 1-7 is for illustrative purposes only and forms no part of the claimed design.
